STITCH CONTROL MECHANISM FOR SEWING MACHINES WITH COMBINED LOWER AND UPPER FEED

Rudolf Reeber, Neukenfer Loh über Munich, Germany, assignor to G. M. Pfaff AG, Kaiserslautern, Pfalz, Germany, a corporation of Germany

Filed July 17, 1963, Ser. No. 295,758

Claims priority, application Germany, July 18, 1962,

P 29,852

9 Claims. (Cl. 112—210)

The present invention relates to stitch control for sewing machines equipped with combined lower and upper work feed means, and more particularly, though not limitatively, to work feeding arrangements comprising a lower feed dog or the like and a needle oscillated in the work feeding direction in synchronism with said feed dog, to act as upper feed means in a manner well known.

More specifically, the invention is concerned with the provision of improved feed stroke control means for machines of the type referred to embodying uni-control and adjusting means for the simultaneous variation of the operating stroke of both said lower and upper feed means and, in turn, of the stitches sewn by the needle in cooperation with a suitable loop taker.

It has been customary heretofore, in an effort to reduce to a minimum the moving masses in machines having an oscillating needle as a work feeding means, to mount the control mechanism for adjusting the needle oscillating amplitude in the direct vicinity of the needle or its oscillating frame or support, that is, in or upon the head and/or the adjoining part of the upper arm of a machine of conventional construction. Stitch control mechanism of this type has the drawback, among others, of occupying an undue amount of space at the very place or location ordinarily required for the mounting of accessory devices or auxiliary sewing aids. Besides, in arrangements of this type, oscillations or vibrations of the machine caused by the eccentric drive and the oscillating masses of the stitch control mechanism may be amplified or accentuated by reason of their increased distance from the center of gravity of the machine located in the upright section of the machine housing or opposite to the sewing head. This, in turn, greatly reduces or limits the operating or sewing speed, a serious drawback especially felt in the case of high-speed industrial or automated sewing machines.

Accordingly, among the objects of the present invention is the provision of stitch control mechanism for adjusting the feed stroke of a sewing machine of the type referred to and equipped with lower and upper feed means, whereby the prior and related difficulties and drawbacks are substantially overcome; which mechanism will fulfill the highest demands encountered in connection with modern industrial sewing operation; which mechanism, in particular its part for the control of the needle oscillations, has the advantage of easy and ready accessibility, to facilitate assembly, lubrication, as well as adjustment and repairs or the like operations; and which is both simple in construction as well as efficient in operation, and can be readily embodied in conventional lower and upper feed type sewing machines.

The invention, both as to the foregoing and its ancillary objects as well as novel objects, will be better understood from the following detailed description of a preferred practical embodiment, taken in conjunction with the accompanying drawing forming part of this specification and in which:

FIG. 1 is a longitudinal cross-section through a sewing machine having lower and upper work feed means and embodying stitch control mechanism constructed

in accordance with the principles of the invention; and

FIG. 2 is an expanded and enlarged perspective view showing in greater detail the essential parts of the stitch control mechanism of the invention.

Like reference numerals denote like parts in both views of the drawing.

With the foregoing objects in view, the invention, according to one form of carrying the same into effect, involves generally the provision in a sewing machine of the type referred to and having a base plate, a housing comprised of an upright at one end of said plate and an overhanging arm extending from said upright in a direction parallel to said plate and terminating in a sewing head, and stitching tool means including a reciprocating needle mounted within said head and a loop taker below said plate to produce stitches in a work piece fed along said plate, of work feed and stitch control means comprising lower and upper work feeding means supported by said head and said plate, respectively, a first drive shaft mounted within said arm which may be the main drive or arm shaft operating the needle for reciprocation in the vertical direction, and a first rockshaft also mounted within said arm parallel to said drive shaft and operably connected to said upper feed means, to intermittently engage and advance the work in synchronism with the stitching operation. According to one embodiment, as shown by the drawing, the upper feed means may consist in the needle frame or support being oscillated in the work feeding direction in synchronism with a feed dog or the like lower work feeding means, whereby the needle acts as the upper feed means in a manner well known. Alternatively, a separate upper feed dog or the like feed means may be provided synchronized with the lower feed means and controlled by mechanism according to the invention, as will become further apparent as the following description proceeds.

There is furthermore provided in accordance with the invention a second drive shaft being in driving connection with said first drive shaft and mounted below the work supporting plate of the machine, said second drive shaft being advantageously constituted by the loop taker drive shaft for the operation of a loop taker in synchronism with the needle, in a manner well known to those skilled in the art. There is further provided a second rockshaft also mounted below said plate parallel to said second drive shaft and operably connected to the lower work feed means, to intermittently engage the work in synchronism with the upper feed means. Finally, the invention embodies unitary stitch control means for adjusting the feed advance stroke of both said upper and lower feed means and including essentially first motion-transmitting mechanism operatively connecting said first drive shaft with said first rockshaft, to transmit rotary motion of said first drive shaft into oscillating motion of said first rockshaft for the operation of said upper feed means, second motion-transmitting mechanism operably connecting said second drive shaft with said second rockshaft, to transmit rotary motion of said second drive shaft into oscillating motion of said second rockshaft for the operation of said lower feed means, a first rotary control shaft operably embodied in said first mechanism for adjusting the oscillating amplitude of said first rockshaft and, in turn, the feed stroke of the upper feed means, a second rotary control shaft operably embodied in said second mechanism for adjusting the oscillating amplitude of said second rockshaft and, in turn, the feed stroke of said lower feed means, and uni-control means to commonly adjust both said control shafts for varying the feed strokes of both feed means or the stitching length, respectively.

According to a preferred embodiment, the uni-control means in the form of an adjusting knob or disk is mount-

ed upon the outside of the upright of the sewing machine housing below the usual hand or flywheel of the machine and connected with both said control shafts through suitable motion transmitting linkage devices. As a consequence, the drawbacks and defects, in particular the problems of vibration, inherent in the prior stitch control arrangements are substantially eliminated or minimized by the invention while at the same time allowing of ready access to the control mechanism or parts thereof.

The motion-transmitting mechanism connecting the respective drive and rockshafts advantageously may consist of an eccentric having an eccentric rod, a lever having a pivot at one end and having its opposite end pivotally or rotatively connected to the end of said eccentric rod, to form a knuckle joint, means to transmit oscillating motion of said lever to the rockshaft operating the respective feed means, and means to vary the position of said pivot by the associated control shaft, to thereby control the amplitude of the oscillating motion transmitted to said shaft, in a manner as will become further apparent from the following detailed description of the drawing.

The arm or drive shaft 2 mounted in the upper arm of the housing 1 of a conventional sewing machine serves to reciprocate, by way of a crank 3 and link 4, the needle bar 5 carrying a needle, said bar being mounted in a frame or support 7 rotatably supported or journaled upon a stationary pin or pivot 6, to cause the needle to oscillate in the work feeding direction and to act as upper work feeding means in conjunction with a lower feed dog or the like feed means 12. The armshaft 2 drives the loop taker shaft 9, mounted below the base or work-supporting plate of the machine, through a chain or the like transmission 8, shaft 9 serving to operate in a known manner a loop taker (not shown) mounted below said plate for cooperation with the needle in forming stitches in a work piece fed along said plate by the combined action of said feed dog and the needle acting as upper feed means.

The sewing machine is further equipped with first control mechanism 10 for adjusting the oscillating amplitude of the needle supporting frame 7 and to control the upper feed stroke, and a second similar control mechanism 11 for adjusting the feed stroke of the feed dog 12, mechanism 10 being advantageously disposed upon the outside of the housing 1 or of the upright section of the latter and below the hand- or flywheel 13 and being supported by a control shaft 14 journaled in said housing and extending parallel to the main drive shaft 2.

In the following, there will be at first described the construction of the control mechanism 10. Secured to the control shaft 14 is a first U-shaped member 15 between the arms 15a and 15b of which there is rotatively supported, by a pair of pins 17 and 17a, a further U-shaped member 16 having arms 16a and 16b which are connected by a shaft or spindle 18 to which is imparted, by way of an eccentric 19 and eccentric rod 20, oscillating motion from the drive shaft 2 with the pins 17 and 17a acting as rotating axis.

A link 21 having one end engaging the spindle 18 has its opposite end rotatively connected to a crank 23 through a pin 22, said crank being in turn secured to a rockshaft 24 parallel to the shaft 2 and journaled in and extending outwardly from the housing. The opposite end of the shaft 24 is connected to a further crank 25 which is, in turn, operably connected to the oscillating needle frame 7 through a link 26, to transmit oscillating motion by said shaft to the needle bar 5.

The control mechanism 11 for the feed dog 12 is connected by way of a crank 28 to a control shaft 29 being parallel to the loop taker drive shaft 9 and journaled in the housing 1. Secured to the free end of the crank 28 is a pin 30 upon which is rotatively mounted a lever arm 31 which is in operative connection, by way of a shaft or spindle 32, a further lever arm 33, pin 34 and a crank 35, with a rockshaft 36 also journaled in the housing 1 and being parallel to the loop taker drive shaft 9. Rock-

shaft 36 carries an oscillating member 37 to which is linked the feed dog 12, to operate the latter by the oscillating movements of the lever 31, in the manner further understood from the following. The control and motion-transmitting mechanism 11 is driven by the loop taker shaft 9 through an eccentric 38 and eccentric rod 39, the latter rotatively engaging the spindle 32 in a manner substantially analogous to the corresponding parts of the control mechanism 10 for the upper feed means, to convert rotary motion of the shaft 9 into oscillating motion of the shaft 36 for the intermittent operation of the feed dog 12 in synchronism with the needle operating means or frame 7.

The control shaft 14 of the motion-transmitting and control mechanism 10 is connected through a crank 40 and link 41 with a further crank 42 which is mounted upon the control shaft 29 of the mechanism 11, crank 42 being in turn connected, through a link 43 and a pair of ball or universal joints 43a and 43b, with one end of a double-arm lever 44 rotatable about a stationary shaft or axis 45 supported by the housing 1. The opposite arm of the lever 44 engages the cam-shaped groove 46a of an adjusting knob or disk 46 rotatively mounted upon the outside of the upright section of the housing 1.

Encircling the shaft 29 is a coil spring 47 having one end fixedly connected to the housing 1 and having its opposite end engaging or connected to said shaft, whereby to urge both the control shafts 14 and 29 in the direction of forward feed of the work piece being operated on. In order to reverse the feeding or stitching direction, there may be provided a control key 48 secured to the end of the shaft 45 projecting outwardly of the housing 1.

The mechanism 10, mounted substantially outside of the housing 1, is advantageously protected by a cover 49 which may also serve to conceal part of the hand wheel 13 and of the control knob or disk 46, except for a relatively small adjusting aperture.

In operation, both control mechanisms 10 and 11 are adjusted by the common or uni-control adjusting knob 46, being set to a predetermined position corresponding to a desired stitching length, whereby to rotate the control shaft 29 by the action of the spring 47 until the lever 44 engages the edge of the groove 46a acting as an abutment therefor. Rotation of the shaft 29 further results in the rotation of the crank 28, whereby to displace the pin 30, acting as pivot or rotating axis of the lever 31, relative to the pin 34. In the position shown with both said pins 30 and 34 aligned along a common axis, the lever 33 has no component of movement in the lengthwise direction, whereby no oscillating motion will be imparted to the rockshaft 36 of the feed dog 12. This adjusting position corresponds, therefore, to the rest or zero feed condition of the machine. On the other hand, with the pin 30 serving as a pivot for the lever 31 being displaced relative to the pin 34 by the adjustment of the control shaft 29 through the adjusting knob 46, the spindle 32 being actuated by the eccentric rod 39 causes the lever 31 to carry out a rotating motion about the pivot 30, in such a manner as to impart to the lever 33, in addition to said rotary motion, a translatory motion or motion in its lengthwise direction. This latter motion is transmitted by means of the crank 35 to the rockshaft 36 and oscillating member 37, to operate the feed dog 12. The feed stroke is determined by the amount of rotation of the control shaft 29, or extent of relative displacement of the pins 30 and 34, whereby to enable a gradual feed stroke control between zero and a maximum by rotation of the knob or disk 46.

Rotation of the control shaft 29 by the knob 46 also causes a corresponding rotation of the control shaft 14 of the needle oscillation control mechanism 10 by way of the crank 42, connecting link 41 and crank 40. As a consequence, arms 15a and 15b of the member 15 being secured to the shaft 14 cause a rotation of the

arms 16a and 16b of the member 16, whereby to displace the pins 17 and 17a, forming the rotating axis of the member 16, relative to the spindle 22. Accordingly, the arms 16a and 16b, in analogy to the corresponding parts of the mechanism 11, carry out a pure rotating motion about the pins 17 and 17a as a result of the oscillations of the spindle 18 imparted thereto by the eccentric rod 20. Link 21, aside from this rotary motion, is subjected to a translatory motion, whereby to result in an oscillating motion of the crank 23 and, in turn, of the crank 25 connected to the needle oscillating frame 7 through the rockshaft 24. As a consequence, the oscillating motion of shaft 25 is transmitted by the link 26 connected to the crank 25 to the needle frame 7, whereby with the proper design of the mechanisms 10 and 11 the needle will be oscillated in the feeding direction in synchronism and cooperation with the feed dog 12 for any feed stroke adjustment effected by the control of the knob 46.

In the foregoing the invention has been described in reference to a specific illustrative device. It will be evident, however, that variations and modifications, as well as the substitution of equivalent parts and elements for those shown herein for exemplification may be made without departing from the broader scope and spirit of the invention as set forth in the appended claims. The specification and drawing are accordingly to be regarded in an illustrative rather than in a restrictive sense.

I claim:

1. In a sewing machine of the type having a base plate, a housing including an upright and an overhanging arm extending therefrom in a direction parallel to said plate and terminating in a sewing head, a reciprocating needle mounted within said head, to produce stitches in a workpiece fed along said plate, a needle drive shaft within said arm operably connected to said needle, to reciprocate said needle in the vertical direction, and a loop taker drive shaft in driving connection with said first drive shaft and mounted below said plate; work feeding means comprising in combination:

(1) a first rockshaft mounted within said arm and operably connected with said needle, to oscillate the same in the work feeding direction, to provide first work feeding means of said machine,

(2) a work feeding dog,

(3) a second rockshaft mounted below said plate and operably connected to said dog, to provide second work feeding means of said machine, and

(4) drive and unitary stitch control means to operate said first and second rockshaft and to adjust the feed advance strokes of both said work feeding means, comprising:

(a) first motion-transmitting mechanism operably connecting said needle drive shaft with said first rockshaft, to convert rotary motion of the needle drive shaft into oscillating motion of said first rockshaft,

(b) second motion-transmitting mechanism operably connecting said loop taker drive shaft with said second rockshaft, to convert rotary motion of said loop taker shaft into oscillating motion of said second rockshaft,

(c) a first rotary control shaft of said first mechanism operative to control the feed stroke of said needle in accordance with the angular adjusting position of said first control shaft,

(d) a second rotary control shaft of said second mechanism operative to control the feed stroke of said dog in accordance with the angular adjusting position of said second control shaft, and

(e) uni-control means to adjust both said control shafts, to simultaneously vary the feed strokes of said needle and feed dog in synchronism.

2. In stitch control mechanism for a sewing machine with lower and upper work feed as claimed in claim 1, said unitary control means comprising an adjusting knob and motion transmitting linkage means connecting said knob with both said control shafts.

3. In stitch control mechanism for a sewing machine with lower and upper work feed as claimed in claim 2, said machine having a flywheel disposed upon the end of said needle drive shaft projecting outwardly from said upright, and said adjusting knob being disposed upon the outside of said upright underneath said flywheel.

4. In a sewing machine of the type having a base plate, a housing including an upright and an overhanging arm extending therefrom in a direction parallel to said plate and terminating in a sewing head, a reciprocating needle mounted in said head, a first drive shaft mounted in said arm and operably connected with said needle, and work feeding means to intermittently advance a workpiece along said table for cooperation with said needle and a loop taker to form stitches, said feeding means comprising in combination:

(1) upper work feeding means mounted upon said head,

(2) lower work feeding means mounted below said plate,

(3) a second drive shaft in driving connection with said first drive shaft and mounted below said plate,

(4) a first rockshaft mounted within said arm and operably connected with said upper work feeding means,

(5) a second rockshaft mounted below said plate and operably connected with said lower work feeding means, and

(6) drive and unitary stitch control means to operate said first and second rockshafts and to adjust the feed advance strokes of both said work feeding means comprising:

(a) first motion-transmitting mechanism operably connecting said first drive shaft with said first rockshaft, to convert rotary motion of said first drive shaft into oscillating motion of said first rockshaft,

(b) second motion-transmitting mechanism operably connecting said second drive shaft with said second rockshaft, to convert rotary motion of said second drive shaft into oscillating motion of said second rockshaft,

(c) a first rotary control shaft of said first mechanism operative to control the feed stroke of said upper feeding means in accordance with the angular adjusting position of said first control shaft,

(d) a second rotary control shaft of said second mechanism operative to control the feed stroke of said lower feeding means in accordance with the angular adjusting position of said second control shaft, and

(e) uni-control means to adjust both said control shafts, to simultaneously vary the feed strokes of said upper and lower feed means in synchronism.

5. In stitch control mechanism for a sewing machine with lower and upper work feed as claimed in claim 4, said unitary control means comprising an adjusting knob and separate motion-transmitting linkage means connecting said knob with both said control shafts.

6. In stitch control mechanism for a sewing machine with lower and upper work feed as claimed in claim 5, said first drive shaft carrying a flywheel at its end projecting outwardly from said upright, and said adjusting knob being disposed upon the outside of said upright underneath said flywheel.

7. In stitch control mechanism for a sewing machine with lower and upper work feed as claimed in claim 4, said unitary control means comprising an adjusting knob

having a cam, motion transmitting linkage means having an input element operably engaged by said cam and having a pair of output elements each arranged, respectively, to actuate one of said control shafts.

8. In stitch control mechanism for a sewing machine with lower and upper work feed as claimed in claim 4, each said first and second motion-transmitting mechanism comprising an eccentric rod connected to an eccentric mounted upon the associated drive shaft, a first lever having a normally stationary first pivot at one end and having its opposite end rotatively connected to the end of said rod, a second lever having a pivot at one end connected to the associated rockshaft and having its opposite end rotatively connected to the end of said rod, and means to adjust the position of said first pivot by the associated control shaft, to vary the amplitude of the oscillations transmitted to said rockshaft.

9. In a sewing machine of the type including stitch-forming means, a first drive shaft operably connected to said stitch-forming means, and intermittent work feeding means to produce stitches in a workpiece in cooperation with said stitch-forming means, said work feeding means comprising in combination:

- (1) a first feeding device,
- (2) a first rockshaft operably connected to said first device, to intermittently engage and advance the work operated on,
- (3) a second feeding device,
- (4) a second rockshaft operably connected to said second feeding device, to intermittently engage and advance the work in synchronism with said first device, and
- (5) drive and unitary stitch control means to operate said rockshafts and to adjust the feed advance strokes of both said devices comprising:

5

10

15

20

25

30

- (a) first motion-transmitting mechanism operably connecting said first drive shaft with said first rockshaft, to convert rotating motion of said first drive shaft into oscillating motion of said first rockshaft,
- (b) a second drive shaft in driving connection with said first drive shaft,
- (c) second motion-transmitting mechanism operably connecting said second drive shaft with said second rockshaft, to convert rotary motion of said second drive shaft into oscillating motion of said second rockshaft,
- (d) a first rotary control shaft of said first mechanism operative to control the feed stroke of said first device in accordance with the angular adjusting position of said first control shaft,
- (e) a second rotary control shaft of said second mechanism operative to control the feed stroke of said second device in accordance with the angular adjusting position of said second control shaft, and
- (f) uni-control means to adjust both said control shafts, to simultaneously vary the feed strokes of said devices in synchronism.
